INVENTOR:

HARRY MESSNER AUSTIN,

By Arthur E. Gaige,
Attorney.

UNITED STATES PATENT OFFICE

HARRY MESSNER AUSTIN, OF CHESTNUT HILL, PENNSYLVANIA, ASSIGNOR TO CHARLES BLUM, OF PHILADELPHIA, PENNSYLVANIA

MOVING SIGN

Application filed February 21, 1929. Serial No. 341,592.

It is the object and effect of my invention to provide means to successively display a series of pictures or advertising matter. The embodiment of my invention hereinafter described is adapted to be automatically operated by reciprocatory movement of one element thereof, to alternately shift two series of display devices carried by respective endless belts. That embodiment of my invention was 5 designed as an accessory to a coin-controlled dispensing mechanism such as described in my copending application Serial No. 311,997 October 12, 1928, which includes a plunger which reciprocates during the dispensing operation and to which said reciprocatory element of the present invention may be attached.

As hereinafter described, the reciprocatory member is a flexible cable which is normally 20 retracted by a spring but which may be drawn out by the movement of the dispensing mechanism to which it is attached. That is to say, the operation of that embodiment of my invention is effected by the coordination of its 25 cable spring with a moving element of the dispensing device. However, said cable may be manually or otherwise moved in opposition to the stress of said spring.

My invention includes the various novel 30 feature of construction and arrangement hereinafter more definitely specified.

In said drawings; Fig. I is a fragmentary front elevation of a coin-controlled dispensing mechanism with a convenient embodiment 35 of my invention applied thereto.

Fig. II is a fragmentary vertical sectional view of the moving sign device indicated in Fig. I; taken on the line II, II in that figure, but on a larger scale.

Fig. III is a fragmentary vertical sectional view of said sign device; taken on the line III, III in Fig. II.

Fig. IV is a fragmentary plan sectional view, taken on the line IV, IV in Figs. II and III.

Fig. V is a partly sectional elevation, taken on the line V, V in Fig. IV and showing the construction and arrangement of the spring motor for the cable.

Fig. VI is a partly sectional elevation of

the ratchet clutch mechanism, indicated in Fig. IV; taken on the line VI, VI in that figure.

Fig. VII is a partly sectional elevation of the ratchet clutch mechanism, indicated in Fig. IV; taken on the line VII, VII in that figure.

Referring to Fig. I; the cabinet 1 is adapted to contain a coin-controlled dispensing mechanism such as above contemplated, having the coin inlet slot 2 at the front wall 3 thereof, and the vertically reciprocatory element 4 therein, which reciprocates during the dispensing operation.

The moving sign device is mounted in the 65 casing 5 which is rigidly connected with said front wall 3, and includes two similar display openings 7 and 8 which are covered with respective transparent glass panels 9.

Said casing 5 contains two endless belts 11 70 which may be transparent photographic or other picture films adapted to be illuminated by incandescent lamps 12. Said films 11 are hung upon respective idle rollers 14 which have radially projecting studs 15 engaging 75 perforations 16 at the margins of said belts; whereby said belts are retained in proper relation with said rollers. Said rollers are supported upon respective shafts 18 journaled in respective pairs of bearings 19 which are adapted for slight vertical movement and normally upheld by springs 20 which keep the belts taut.

Said sign belts 11 are arranged to be positively progressed by engagement with respective rollers 22 and 23 which have studs 24 and 25 adapted to engage said perforations 16 in the belts and to positively shift the latter by the turning movement of said rollers.

Said roller 22 is rigidly connected with the shaft 27 which is journaled in the bearings 28 on said casing 5. Said roller 23 is rigidly connected with the tubular shaft 30 which is journaled on said shaft 27. Said shafts 27 and 30 are connected with actuating mechanism whereby the belts 11 are intermittently and alternately progressed downward at the front thereof, as indicated by the arrow in Fig. II. That is to say, one 90 95 100

of said belts is held stationary to display the advertising picture or other matter thereon, while the other belt is moved, and the respective lamps 12 may be lighted behind the stationary belt to illuminate it, and extinguished behind the moving belt so that the public is attracted by the alternate flash-lighting of the display panels 9.

Said actuating mechanism includes the spring motor drum 32 which has the gears 33 and 34 rigidly connected therewith by the sleeve 35. Said drum and gears are mounted to turn freely on the shaft 36 which is held stationary in the bearings 37 and 38, conveniently extending in rigid relation with said cabinet wall 3, as indicated in Fig. IV. Said drum 32 incloses the spiral spring 40 which has its inner end engaged with the stationary stud 41 on said shaft 36 and its outer end engaged with the stud 42 which is fixed in said drum. Said drum carries, upon its outer surface, the flexible connector 45 which is attached thereto at its end 46. Said flexible connector 45, which is preferably a cable formed of a plurality of fine wires, but which may be a unitary strip of metal, chain or cord, is connected at its lower end to said vertically reciprocatory element 4 of the dispensing mechanism and, when pulled downward by the latter, rotates the drum in the direction of the arrow shown in Fig. V, so as to wind the spring 40 around the stationary shaft 36. When said element 4 is moved upward by the action of the dispensing mechanism, the drum 32, being thus released, is turned in the opposite direction to the arrow in Fig. V, by the unwinding stress of said spring 40. Such construction and arrangement serve, of course, to turn the gears 33 and 34 together, in alternately opposite directions. Said gear 33 is in mesh with the idle gear 47 which is journaled on the stud shaft 48 which is held stationary in said casing 5, and said gear 47 is in mesh with the gear 50 which is loosely journaled on said shaft 27, as indicated in Fig. IV, between the adjacent end of the casing 5 and the ratchet wheel 51 which is pinned or otherwise secured in stationary position on said shaft 27. As indicated in Figs. IV and VI; said gear 50 has the pawl 52 pivoted upon the stud 53 carried by said gear, and is spring pressed into engagement with said ratchet 51 by the spring 55 also carried by said gear. Therefore, the effect of the downward movement of said cable 45 is to turn said shaft 27 in the direction of the arrow on Fig. VI, and, consequently, downwardly progress the belt 11 displayed at the opening 7.

The above described turning movement of the gear 33 is, of course, accompanied by a similar turning movement of the gear 34 which is in mesh with the gear 57 which is loosely journaled on said tubular shaft 30 in coaxial relation with said shaft 27 and held

between the annular flange 59 on said shaft 30 and the ratchet wheel 60 which is rigidly connected with said shaft 30 by the screw key 61, or otherwise. As indicated in Figs. IV and VII; said gear 57 has the pawl 62 pivoted upon the stud 63 carried by said gear, and is spring pressed into engagement with said ratchet 60 by the spring 65 also carried by said gear. Therefore, the effect of the downward movement of said cable 45 is to turn said gear 57 idly; the pawl 62 being drawn backward over the ratchet 60, without turning the latter, and thus leaving the shaft 30 stationary; so that the belt 11 displayed in the opening 8 remains stationary while the other belt is shifted in the opening 7 as above described.

However, when said element 4 of the dispensing mechanism moves upward, permitting the drum 32 to be turned by its spring 40, in the direction opposite to the arrows in Figs. IV and V, the operation above described is reversed, i. e., the gear 50 carries the pawl 52 idly backward, leaving the shaft 30 and the belt 11 in the display opening 7 stationary, while the gear 57 is then turned in the direction opposite to the arrow in Fig. VII and, by the pawl 62, turns the shaft 30 to shift the belt in the display opening 7. Thus, said belts 11 are alternately held stationary and shifted during the reciprocatory movement of the element 4 of the dispensing mechanism.

As above contemplated; the alternate operation of the belts 11 may be accompanied by alternate lighting of the lamps 12; so that each time each of said belts is held stationary, while the other is moved, the stationary belt is illuminated while the moving belt is not, thus affording a flash-lighting effect which is more attractive of public attention than a constant illumination of the sign device would be. Such lighting effect may be attained by any suitable device adapted to be actuated by said reciprocatory element 4, or otherwise. For instance, as indicated in Fig. II, said lamps 12 may be provided with respective terminals 66 and 67 adapted to be alternately included in the circuit with the conductor 68 by means of the switch lever 70 which is fulcrumed at 72 in said cabinet 1. Said lever 70 may be shifted from the terminal 66 to the terminal 67 by upward movement of said member 4 at the upper limit of the stroke of the latter. Said switch lever 70 may be shifted from the terminal 67 to the terminal 66 by downward movement of said member 4, at the lower portion of its stroke, in contact with the lever 74 which is fulcrumed at 75 in said cabinet 1 and connected with the lever 70 by the link 76.

However, I do not desire to limit myself to the precise details of construction and arrangement herein set forth, as it is obvious that various modifications may be made

therein without departing from the essential features of my invention, as defined in the appended claims.

I claim:

1. In a moving sign, the combination with two endless belts, carrying the things to be displayed; of means adapted to intermittently shift said belts, including two independently rotatable rollers engaging said belts; a rotary drum; ratchet means adapted to alternately hold each of said rollers stationary, while the other is shifted by turning movement of said drum; a spring motor mechanism connecting said rollers and drum; and a cable carried by said drum; whereby said spring may be stressed to turn said rollers by traction on said cable.
2. In a moving sign, the combination with two endless belts, carrying the things to be displayed; of means adapted to intermittently shift said belts, including two independently rotatable rollers engaging said belts; a rotary drum; ratchet means adapted to alternately hold each of said rollers stationary, while the other is shifted by turning movement of said drum; said ratchet means including a single rotor having two circular series of ratchet teeth and pawls respectively engaging said teeth; a spring motor mechanism connecting said rollers and drum; and a cable carried by said drum; whereby said spring may be stressed to turn said rollers by traction on said cable.
3. The combination with a coin-controlled dispensing mechanism; of a moving sign device, including two endless belts having respective series of sign devices; means adapted to alternately shift said belts to alternately successively display said respective series of sign devices; and means connecting said coin-controlled dispensing mechanism and said belt shifting mechanism; whereby said sign devices are adapted to be alternately moved by successive movements of said dispensing mechanism.
4. In a moving sign, the combination with an endless belt carrying the thing to be displayed; of means adapted to intermittently shift said belt, including a drum and a cable adapted to turn said drum; means adapted to illuminate said belt when stationary; and means adapted to suppress the illumination when said belt is being moved.
5. In a moving sign, the combination with two endless belts, carrying things to be displayed; of means adapted to intermittently and alternately shift said belts; and means adapted to alternately illuminate said belts; and means adapted to control the illumination of said belts, in connection with the means for moving them.

In testimony whereof, I have hereunto signed my name at Philadelphia, Pennsylvania, this 8th day of February, 1929.

HARRY MESSNER AUSTIN.
